UNITED STATES PATENT OFFICE.

DONALD H. REEVES, OF DAYTON, OHIO.

PNEUMATIC PUMP.

Application filed April 24, 1919. Serial No. 292,319.

To all whom it may concern:

Be it known that I, DONALD H. REEVES, a citizen of the United States, residing at 351 Edgewood Ave., Dayton, in the county of 5 Montgomery and State of Ohio, have invented certain new and useful Improvements in Pneumatic Pumps, of which the following is a specification.

This invention relates to a pneumatically 10 operated gasoline pump intended to be used in co-operation with the gasoline tank of an airplane.

It is desirable in airplane work to have the 15 gasoline fed to the small gravity tank, commonly located in the upper plane of an airplane, by air pressure. This has been done formerly by putting the whole gasoline tank itself under pressure. This is obviously objectionable, because a single bullet hole 20 through any part of the main tank would put the gasoline feed out of commission.

The principal object of this invention is to provide a means for pneumatically feeding the gasoline to the gravity tank without subjecting the main gasoline tank to any higher 25 pressure than the atmospheric pressure.

It is a further object of this invention to provide a gasoline pump that is located in the bottom of the main gasoline tank, practically 30 forming a sump, the gasoline flowing under the influence of gravity alone into the pressure chambers of the pump.

It is a further object of this invention to provide a gasoline pump in which two pressure 35 chambers are provided, to which chambers air pressure is alternately admitted, and then alternately vented. This alternate pressure-subjecting and venting action is automatic in its operation.

40 Other objects and advantages will appear as the description proceeds.

In the drawings illustrating one embodiment of my invention, Figure 1 is a perspective view of the assembled pump. Figure 2 is a similar view with the pump cover removed. Figure 3 is a plan view of the cover. Figure 4 is an enlarged section taken on the line 4—4 of Figure 3. Figure 5 is a section, on a scale smaller than that of 45 Figure 4, taken on the broken line 5—5 of Figure 3. Figures 6 and 7 are diagrammatic sectional views to illustrate the operation of the reversing valve. Figure 8 is an enlarged section view taken on a vertical plane passing through the line 8—8 of Figure 1. 50

Figure 9 is a reduced view partly in elevation and partly in section, showing the relation of the pump to the gasoline tank.

The pump comprises a main body element 1 which is divided by the partition 2 into the float pressure chamber 3 and the auxiliary pressure chamber 4. An escape pipe 5 for the gasoline is provided with branches 6 and 7 that are bolted, by bolts 6' and 7', to plates 8 on the side of the casing 1, to register with appropriate openings from the two pressure chambers 4 and 3, respectively. Each of the plates 8 carries an opening 8' that is controlled by the disk 9 being pressed thereover by the spring 10, thus forming a one way valve. Each plate 8 may be provided with a lip 11 extended downwardly so that when air pressure is admitted to the chamber 4 gasoline will be drained or forced from the chamber as far down as the lower level of the lip.

The cover plate 12 is secured by a plurality of screws 13 to body 1 to complete the pressure chambers 3 and 4. This cover plate is provided with the gasoline inlet pipes 14 and 15, that open respectively into the pressure chambers 4 and 3, each being controlled by one way valves 16, mounted loosely on pins 17 to move outwardly. Only one of these is shown in Figure 8. The other not shown, is precisely similar.

Mounted on the cover plate 12, preferably over the main pressure chamber 3, is a float chamber comprising a vertical, cylindrical wall 18, and a top plate 19. The wall 18 is flanged as at 18', for securement to the cover plate 12, the cover plate 12 being cut away just below the float chamber so that the interior thereof is in communication with the interior of the float chamber.

Mounted in the top wall 19 of the float chamber is a valve mounting casting 20 which is provided with a series of air pressure and air vent passages. A vertically disposed cylindrical passage 21 is drilled in the casting 20, the passage 21 being open at its lower end into the float chamber. A horizontally drilled passage 22 communicates with the passage 21 at its upper end to also communicate with the float chamber.

The casting 20 has drilled therein passages 23 and 24 which, through the hole 25 are in communication with the passage 21 at the point shown. A reversing valve, comprising an upper valve disc 26 and a lower

valve disc 27 carried by a valve stem 28 is movable in the valve passage 21. It should be noted that the disc 26 when in its uppermost position is just below the opening 22 and that at the same time the disc 27 is just below the opening 25.

Referring now to Figure 5, casting 20 is also provided with a passage 29, for the admission of air. Passage 29 is in communication with passage 21, through the hole 30.

The hole 30, it should be noted, is below the valve disc 27 when the valve is in its uppermost position. The valve is shown in its uppermost position in both Figures 4 and 5.

Referring to Figure 5, casting 20 is further provided with the vent passage 31, which through the hole 32 is in communication with the valve passage 21, at a point below the valve disc 26 when in its uppermost position.

An air pressure pipe 33 leads compressed air to the top of the float chamber and into the air passage 29. A short pipe 33', projects to the outside of the body 1, and registers with pipe 33. A compressed air pipe, not shown, is attached to 33'. A pipe 34 that at one end 35 communicates with the auxiliary pressure chamber 4, at its other end 34' communicates with the already described passages 23 and 24. The vent passage 31 is in communication with a vent pipe indicated by dotted lines at 36 in Figure 1. This pipe 36 passes upwardly through the gasoline in which the pump is immersed and opens into the top of the gasoline tank.

The casting 20 is provided with downwardly extending arms, one of which is indicated at 37, which carry at their lower ends a disc 38, provided with an aperture 39 in which aperture the lower end of the valve stem 28 is slidably up and down. The valve stem 28 is provided, toward its upper end with a flange 40 and toward its lower end with a shoulder 41, that is screw threaded on the valve stem.

A sheet metal float 42, annular in form surrounds the casting 20 and part of the standard 37 loosely so as to be slidable up and down with respect to said standard. Suitably secured to the inner wall 43 of the float is a bracket 44 provided with a hole 45, through which hole the valve stem 28 passes with a loose fit. Springs 46 and 47 are respectively positioned between the flange 40 and bracket 44, and the bracket 44 and shoulder 41.

A latch element 48 provided with an upper latching shoulder 49 and a lower latching shoulder 50, is carried by the arm 51, which is mounted at its lower end 52 in the disc 38 so as to have a slight lateral movement. The arm 51 is provided with a bevel portion 53, a straight portion 54, and a reversely beveled portion 55. A spring 56, mounted on the standard 37 by rivets 57,

presses against the arm 51 to press it to the left of Figure 4.

The pump of this invention is designed to be mounted in the bottom of a gasoline tank and acts practically as the sump thereof. The pump is held in the bottom of the tank by suitable bolts or screws passing through the flange 58. The cover plate 12 and float chamber 18 and associated parts are completely immersed in gasoline.

The operation of the device will now be described. With the valve positioned as in Figures 4, 5 and 6, the pressure chamber 3 presumed full of gasoline that has flowed in by gravity through the pipe 15, the float will of course be in its uppermost position as shown in Figure 4. With the valve also in its uppermost position, it is apparent that air pressure will be admitted through the aperture 30 to the interior of the float chamber. This air pressure will force the gasoline in the chamber 3, out through the pipes 7 and 5 up to the gravity tank, not shown, or other desired point. At the same time it should be noted that the auxiliary chamber 4 is in communication with the vent 32 through the hole 25, passages 24 and 23 and pipe 34. While then the air pressure is forcing gasoline out of the chamber 3 the gasoline is flowing into the chamber 4 through the inlet pipe 14, the air that it displaces escaping through the pipe 34 and vent 32 and pipe 36 into the top of the gasoline tank.

As the gasoline leaves the chamber 3 the float 42 gradually falls. The latching shoulder 49 however during this operation holds the valve stem 28 in the uppermost position as shown in Figure 4. As the float falls it carries with it the bracket 44, which rides over the beveled portion 53, straight portion 54 and on to the beveled portion 55, until finally it forces the arm 51 to the right. During its downward movement the bracket 44 continually compresses the spring 47 and releases spring 46. By the time that the bracket 44 has reached the bevel portion 55, the spring 47 is rather tightly compressed and spring 46 relieved. At this instant the latch 48 will be forced so far to the right as to disengage from the shoulder 40 whereupon the spring 47, acting on the shoulder 41, will move the valve stem 28 quickly downwardly so that it reaches the position shown in Figure 7.

This movement of the valve stem reverses the flow of air and gasoline described above. That is to say, the air pressure entering through the hole 30 is turned into the auxiliary chamber 4 through the hole 25 and passages 24 and 23 and pipe 34'. This will cause the gasoline to be forced out of the chamber 4 into the pipes 6 and 5 and thence to the gravity tank, or other desired point, not shown. The float chamber, through the

passage 22 will be in communication with the vent 32, so that the air may escape from the float chamber through the vent pipe 36 to the top of the tank. This relieves the air pressure in the float chamber, whereupon it will fill by gasoline flowing into it through the inlet 15 under the influence of gravity alone.

At this point it should be stated that the valve stem 28 is held in its lowermost position, as shown in Figure 7, by the latching shoulder 50 having engaged over the top of the flange 40. As the gasoline flows into the chamber 3 the float 42 starts to rise again. As the float rises the bracket 44 passes over the straight portion 54 of the latch member 51 and onto the beveled portion 53, it during this upward movement putting the spring 46 under compression and releasing spring 47. By the time that the bracket 44 has gotten well onto the bevel portion 53 the spring 46 is fairly well compressed. Continued upward movement of the float and bracket 44 causes the latch 51 to be moved to the right to unlatch the shoulder 50 from the flange 40, where upon the spring 46 will move the valve stem 28 back to the position shown in Figures 4 and 6, which causes the cycle of operations to start over again. This valve reversing means and alternately filling and emptying of the two pressure tanks is entirely automatic in its action.

While I have illustrated my invention in considerable detail, it should be understood that it may be carried out in many other

ways as defined within the scope of the following claims.

I claim:—

1. In combination with a closed in main fuel tank, an auxiliary filling chamber in communication with said tank, and fed by gravity from said tank, a valve to control the flow of fuel from said main fuel tank, means for emptying the fuel from said filling chamber, a float controlled means in said filling chamber for automatically communicating said filling chamber with the top of said main fuel tank, said float controlled means comprising an energy storing spring device operated by said float and held by a latch, said latch being automatically released by a cam controlled by the float of said float controlled means.

2. In combination with a closed in main fuel tank, an auxiliary filling chamber in communication with said tank, and fed by gravity from said tank, a valve to control the flow of fuel from said main fuel tank, pneumatic means for emptying the fuel from said filling chamber, and a float controlled means in said filling chamber for automatically communicating said filling chamber with the top of said fuel tank, said float controlled means comprising an energy storing spring device operated by said float and held by a latch, said latch being automatically released by a cam controlled by the float of said float controlled means.

In testimony whereof I affix my signature.
DONALD H. REEVES.
